(57) **CLAIM**

The ornamental design for a bottle sterilizing device, as shown and described.

DESCRIPTION

FIG. 1 is a front elevational view of a bottle sterilizing device showing a new design;

FIG. 2 is a right side elevational view thereof;

FIG. 3 is a left side elevational view thereof;

FIG. 4 is a top plan view thereof;

FIG. 5 is a bottom plan view thereof; and,

FIG. 6 is a rear elevational view thereof.

The broken lines are for illustrative purposes only and form no part of the claimed design.
